PREVENTION OF FOAMING IN STEAM GENERATION

Lewis O. Gunderson, Park Ridge, Ill., assignor to
Dearborn Chemical Company, Chicago, Ill., a
corporation of Illinois

No Drawing. Application October 28, 1944,
Serial No. 560,899

2 Claims. (Cl. 252—321)

11

This invention relates to a method for conditioning water and, more particularly, for eliminating foaming conditions in steam boilers.

Foaming of boiler water is not, as commonly thought, equivalent to an accumulation of foam on top of the surface of the boiler water. When steam is rapidly withdrawn from a boiler with resultant foaming, there is no water surface within the boiler correlated with the water level indicated in the conventional water glass attached to the boiler. In other words, there is no sharp line of demarcation between solid water and foam in a boiler during rapid steam withdrawal.

The foaming of boiler water is actually a rapid expansion of the water in a steam generating area of the boiler brought about by the fact that rapidly forming small steam bubbles do not coalesce until a definite short time after their formation. As a consequence, the entire volume of water in the generating area is expanded by myriads of bubbles until the thus formed so-called "light water" may fill the steam space and become entrained with the steam leaving the boiler.

In other words, bubbles need not be particularly stable to cause boiler foaming. The stability of the bubbles need only be such that the bubbles last but a very few seconds after passing the plane of the water level indicated in the water glass.

I have now found that the slight degree of stabilization of bubbles which suffices to cause foaming of boiler water may be largely or completely inhibited by the addition to the water of a high molecular weight composition formed by a reaction of polymerized fatty acids derived from drying or semi-drying oils with a nitrogen containing substances selected from the group comprising alkyline diamines, polyalkylene polyamine, hydroxy alkyl amines containing hydrogen directly attached to nitrogen and a primary hydroxy group, and like compounds.

It is therefore an important object of the present invention to provide methods and compositions for preventing foaming in steam boilers, particularly by incorporation with said water of the above disclosed condensation products of polymerized higher fatty acids with aliphatic nitrogen containing compositions.

Other and further features and objects of the

2

present invention will become apparent from the following detailed disclosure and appended claims.

The polymerized higher fatty acids used as such or in the form of their esters in the preparation of the foam inhibiting compounds of the present invention are derived by methods known in the art from drying or semi-drying oils, fatty acids liberated by saponification of such oils, or esters of such fatty acids.

The relationship, for instance, of linoleic acid to its polymerization products may be roughly indicated by the following formulae:

wherein R represents an unsaturated hydrocarbon chain.

It will be seen that the dimeric acid (Formula II) is dibasic, and that the trimeric acid (Formula III) is tribasic. It is not believed that polymers higher than the trimer are formed.

30 In general, a polymerized higher fatty acid may be reacted with the above mentioned basic nitrogen containing compositions either in the form of the free acid or in the form of esters thereof. It is most convenient to use directly 35 the acid or the ester obtained as a product of any one of the several available polymerization processes.

If desired, the free fatty acids derived by saponification from a drying or semi-drying oil such as soy bean oil, corn oil, linseed oil or the like may be polymerized by a simple heat treatment, for instance, at 265° to 275° C. for from 17 to 18 hours. The product is then subjected to distillation at from two or three millimeters of mercury for removal of the unpolymerized fraction. Such a process is disclosed in British Patent No. 428,864 issued to Imperial Chemical Industries, Ltd.

It is also possible to subject the original drying 50 or semi-drying oils to a heat treatment at, say,

285° to 295° C. for twenty hours followed by saponification and fractional distillation under vacuum of the liberated fatty acids to remove therefrom the glycerine and the unpolymerized fatty acids. This method of preparation is also disclosed in the above identified British Patent No. 428,864.

Still another method of preparing polymerized higher fatty acid material involves the methanolysis of soy bean oil or other vegetable oils, removal of liberated glycerine, polymerization of the separated methyl esters by heat treatment or, optionally, by catalytic means, and final separation of the polymerized methyl esters from the unpolymerized methyl esters by distilling off the latter.

The extent of polymerization effected in any one of the above outlined procedures depends, *inter alia*, on the length of time during which polymerization is carried out. For the purposes of the present invention, the dimeric acids and their esters are preferred, and the polymerization is regulated accordingly.

It is apparent that if a dimeric acid (Formula II) is reacted, for instance, with ethylene diamine, with the elimination of water, one possible product has the following formula:

This diacylated product should have a molecular weight of approximately 584, being formed from two molecules of linoleic acid (molecular weight 280) and one molecule ethylene diamine (molecular weight 60), two molecules of water (molecular weight 18) being split off. Nevertheless, the reaction product of the dimeric acid derived from linoleic acid with ethylene diamine may have an actual average molecular weight varying from 750 up to 2,800 or higher. This is believed due to the formation of linear condensation products, for instance, two or more of the molecules designated by Formula IV being joined together by reaction of the free carboxyl groups at the ends of Formula IV with ethylene diamine.

I have found that for the purposes of inhibiting foam formation in boiler water, condensation products of the above indicated nature must have a molecular weight of least 1,000, and that, in general, the efficiency of such compounds increases with molecular weight.

To illustrate more fully the preparation of the foam inhibiting compounds of the present invention, I will describe hereinbelow in some detail the preparation of a polymerized soy bean fatty acids amide by a process including, as an intermediate step, the preparation of a methyl ester of the soy bean fatty acids. Such methanolysis can be effected by the use of 0.25 part sodium hydroxide, sodium methoxide or potassium hydroxide. The reaction is effected by using 2.5 or more moles of methanol in excess of that required, and heating at 70° C. for two hours. Alkali as sodium hydroxide must be maintained in the reaction mixture in order to obtain as nearly as complete a reaction as possible. The following describes in detail the methanolysis and recovery of methanol.

In a fifteen-gallon stainless steel varnish kettle 0.15 kilogram of sodium hydroxide is dissolved in 8.0 kilograms (2.64 gallons) of anhydrous methanol. Then thirty kilograms (8.6 gallons) of alkali refined soy bean oil is added. The kettle is closed and the contents heated at 70° C. with agitation (a temperature range of 65° C. to 75°

C. is satisfactory). After two hours, the mixture is cooled to 60° C. by introducing cooling water into the kettle jacket, and the kettle is opened to allow the addition of sufficient glacial acetic acid (0.225 kilogram) to neutralize the sodium hydroxide originally used. The kettle is again closed, the distillate line opened, and the unreacted methanol distilled off (4.55 kilograms) to a final kettle temperature of 110° C. at fifteen to twenty millimeters pressure. The kettle is again cooled and one kilogram of water added to the mixture. When the mixture has cooled to 40° C., the agitator is shut off and the mixture allowed to settle for two hours. After settling, crude glycerine (4.5 kilograms plus 1.0 kilogram water) is withdrawn from the bottom of the kettle until methyl esters (lighter color) appear in the drainage. The methyl esters removed from the kettle are covered in a separatory funnel and returned to the kettle. Five gallons of water are added to the kettle, the mixture is heated to 45° C. with agitation, and allowed to settle for thirty minutes. The water is withdrawn from the bottom of the kettle, and the washing operation repeated twice. The kettle is closed and the contents heated to 110° C. under a pressure of fifteen millimeters to remove final traces of water. A yield of 29 kilograms of methyl esters is obtained.

Numerous catalysts, including sulfur dioxide and anthraquinone, may be employed for the polymerization of the methyl esters. Sulfur dioxide is particularly suitable, since it reduces the polymerization time from one-half to one-fourth that required when no catalyst is used. The handling of sulfur dioxide is relatively simple, since it can be bubbled through the methyl esters during the polymerization.

The removal of monomer can be readily effected by distilling at pot temperatures up to 270° C. and by the use of super-heated steam in the final stages of the distillation. Reduced pressures of 5 to 10 millimeters are necessary for removal of all but traces of monomeric esters. The polymerization and distillation steps, as performed in a fifteen-gallon varnish kettle, are described in detail as follows:

The kettle is fitted with a $\frac{1}{8}$ inch stainless steel tube for introducing gas into the kettle to a point near the bottom, and a tube for removing gas from the top. In the kettle are placed 34 kilograms of methyl esters, and heat and agitation are applied. The esters are warmed to 100° C., the kettle is evacuated slowly to fifteen millimeters pressure after having been closed, and sulfur dioxide run in through the stainless steel line until the kettle pressure reaches atmospheric. The gas outlet at the top of the kettle is then opened, and sulfur dioxide is run into the kettle and withdrawn continuously during the remainder of the reaction period. The sulfur dioxide is absorbed by bubbling through water. The mixture in the kettle is heated to 295° to 300° C. for eight hours. The mixture is then allowed to cool to 200° C., and vacuum is slowly applied to distill unbodied methyl esters (monomer). The monomer is distilled under reduced pressure until a temperature and pressure of 270° C. and five to ten millimeters are obtained. Any remaining monomeric fat esters are removed by super-heated steam. The residual dimeric esters in the kettle are then cooled to room temperature in vacuo. The distillation yields 19.7 kilograms of monomer and 13.9 kilograms of residual dimeric esters.

Polymerization can also be carried out by simple heating at about 300° C. The effects on soy bean methyl esters of such a bodying treatment carried out for from 2 to 20 hours is tabulated as follows:

Bodied	Residual Ester	Refractive Index at 30° C.	Viscosity in Centipoises at 30° C.	Specific Gravity at 30°/15.6°	Monomer	Dimer	Trimer and Residue	Dimer/Trimer Ratio (molar)
Hours	Per Cent				Per Cent	Per Cent	Per Cent	
2	2.6	1.4534	4.5	0.8753	97.4	1.6	1.0	2.4
4	5.6	1.4545	4.5	0.8765	94.4	3.5	2.1	2.50
8	15.6	1.4567	6.3	0.8855	84.4	9.4	6.2	2.26

The polyamide can be prepared from residual dimeric fat acids or esters thereof. The preparation runs smoothly both with esters and acids, but the reaction is somewhat faster with the acids. The preparation of polyamide from the free dimeric acid is described as follows:

In a fifteen-gallon experimental varnish kettle, 15.82 kilograms of residual dimeric fat acids are heated to 150° C. in an atmosphere of carbon dioxide and 2.30 kilograms of 70% aqueous ethylene diamine is added slowly with vigorous stirring. The reaction proceeds with the loss of water from the kettle due to evaporation of water added in the diamine solution and the dehydration of diamine salts to give amide linkages. After all of the diamine is added (approximately two hours), the temperature is raised to 150° C. Then over a period of ninety minutes, the pressure on the reaction mixture is reduced slowly to thirteen millimeters and the temperature is raised to 200° C. If too rapid a rise of temperature or lowering of pressure is permitted, excessive foaming may result. The reaction mixture is held at 200° C. at thirteen millimeters pressure for ten minutes, and then run into a vat under an atmosphere of carbon dioxide. The charge is allowed to cool until hardened. Then it is removed by inverting and tapping the sides of the vat.

Residual dimeric fat esters may be used instead of acids. With esters, the diamine can be added directly to the esters and the mixture heated to 110° C. Water begins to distill and the reaction temperature needs to be maintained so that the temperature of the distilling vapors does not exceed 100° to 105° C. A short fractionating column which permits some separation of ethylene diamine from water and alcohol is helpful. When 55% of the calculated amount of distillate has been collected, the temperature is raised to 150° C. and then the pressure reduced slowly to fifteen millimeters, and at the same time the temperature is raised to 200° C.

The preparation of a polyamide from linseed oil is carried out similarly to the preparation described hereinabove using soy bean oil as the original starting material. In all such preparations of polyamides, the time and reaction conditions are regulated so as to effect the formation of products having molecular weights of at least 1,000.

Similar foam inhibiting compounds having molecular weights of at least 1,000 may be prepared by reacting polymerized higher fatty acids or esters thereof with polyalkylene polyamines such as diethylenetriamine, triethylenetetramine, tetraethylene pentamine, with propylene diamine, dipropylene triamine, tripropylene tetramine, bu-

tylene diamine, dibutylene triamine and the like. Instead of the polyalkylene polyamines, I may use the hydroxy alkyl amines containing hydrogen directly attached to nitrogen and a primary hydroxy group, such as monoethanolamine, di-

ethanolamine, triethanolamine, methyl diethanolamine, and, in general, primary, secondary and tertiary hydroxy alkyl amines or alkanol amines, such as propanol amines, butanol amines, ethanol butanol amines, diethanol butanol amines, alkyl derivatives of hydroxyl alkyl amines or alkanol amines, alkanol alkylene diamines, alkanol polyalkylene polyamines, ether derivatives of hydroxy amines such as a monoethyl ether of diethanol amine, amino derivatives of polyhydroxy compounds such as 1-amino propane diol-2,3, and glycerol monoamine and the like.

30 Melamine

may also be used instead of the polyalkylene polyamines for condensation with polymerized higher fatty acid compounds, as well as the condensation products of two moles of an alkylene diamine or polyalkylene polyamine with one mole of a dibasic acid such as tartaric acid, oxalic acid, succinic acid, citric acid, maleic acid and malic acid. These condensation products have terminal primary amino groups.

45 The foam preventing compounds of the present invention were prepared by condensing under suitable conditions two moles of a polymeric fatty acid compound with one mole of any one of several of the above disclosed dibasic or polybasic amines or hydroxy amines to form a product in which the primary amino groups or hydroxy groups are acylated. Good results are also obtained by additionally acylating one or more secondary amino groups when secondary amino groups are present in the acylated amine.

55 The foam inhibiting compositions of the present invention may be introduced into steam boiler water in the form of colloidal dispersions that may be stabilized with tannin, gum arabic or pectin. If desired, the foam inhibiting compositions may be introduced into the boiler in the form of a solution in an appropriate solvent, such as isopropyl alcohol. The dosages required are generally quite small, on the order of some few parts per million of boiler water. In general, from a trace to about fifty parts per million of foam inhibiting compounds may be added to boiler water, preferably in combination with tannin. Addition of foam inhibiting compounds may be repeated as required to prevent foaming.

60 Various details may be varied through a wide range without departing from the principles of this invention, and it is, therefore, not my purpose to limit the patent granted hereon otherwise than necessitated by the scope of the appended claims.

65 I claim as my invention:

70 1. The method of generating steam from a

boiler water having a tendency to foam on boiling, which comprises dispersing into said water in an amount sufficient substantially to inhibit the tendency of said water to foam on boiling a compound having a molecular weight of at least one thousand and comprising a linear condensation product of one molecular proportion of ethylene diamine and two molecular proportions of a dimer of an unsaturated higher fatty acid derived from a member of the group consisting of linseed oil fatty acids and soy bean oil fatty acids, and boiling the resulting dispersion to generate steam therefrom.

2. The method of generating steam from a boiler water having a tendency to foam on boiling, which comprises dispersing into said water in an amount sufficient substantially to inhibit the tendency of said water to foam on boiling a compound having a molecular weight of at least one thousand and comprising the linear condensation product of one molecular proportion of ethylene

5 diamine and two molecular proportions of a dimer of an unsaturated higher fatty acid derived from soy bean oil fatty acids, and boiling the resulting dispersion to generate steam therefrom.
